UNITED STATES PATENT OFFICE.

WILLIAM BENSON, OF SAN FRANCISCO, CALIFORNIA.

DESIGN FOR AN OUTER SHIRT.

56,851.

Specification for Design.

Patented Jan. 4, 1921.

Application filed March 15, 1920. Serial No. 366,115. Term of patent 3½ years.

To all whom it may concern:

Be it known that I, WILLIAM BENSON, a citizen of Poland, and a resident of the city and county of San Francisco, State of California, have invented a new, original, and ornamental Design for an Outer Shirt, of which the following is a specification, reference being had to the accompanying drawing, forming part thereof.

Fig. 2 is a perspective view of the outer-shirt viewing it from the rear.

I claim:

The ornamental design for an outer-shirt substantially as shown.

WILLIAM BENSON.
